UNITED STATES PATENT OFFICE.

WILLIAM SCHAAKE, OF PITTSBURGH, PENNSYLVANIA, ASSIGNOR TO WESTINGHOUSE ELECTRIC & MANUFACTURING COMPANY, A CORPORATION OF PENNSYLVANIA.

TROLLEY-CONDUCTOR HANGER.

Application filed February 4, 1921. Serial No. 442,416.

To all whom it may concern:

Be it known that I, WILLIAM SCHAAKE, a citizen of the United States, and a resident of Pittsburgh, in the county of Allegheny, and State of Pennsylvania, have invented a new and useful Improvement in Trolley-Conductor Hangers, of which the following is a specification.

My invention relates to trolley-conductor hangers and it has for its object to provide a device of this character which shall be simple and durable in construction, economical to manufacture and effective in operation.

In practicing my invention I provide a pair of pressed metal conductor-gripping ears or clamps each having a portion pressed out of a wall thereof to receive one of the initially straight free ends of a uniform cylindrical hanger rod of substantially inverted U-shape. After the insertion of the ends of the hanger rod, each clamping member is pressed laterally with respect to the rod to form undulate-wave or corrugate portions in the rod and to shape the rod-receiving portions of the clamping members into interlocking engagement with the rod.

Figure 1 of the accompanying drawings is a view, partially in elevation and partially in section, of a trolley-conductor hanger embodying my invention, as viewed in the direction of the conductor.

Fig. 2 is a view taken at right angles to Fig. 1, and

Fig. 3 is a view taken along the line III—III of Fig. 1.

Similar pressed-metal clamping members 1 and 2, having jaw portions 3 for engagement with a trolley conductor 4 and inwardly-bent engaging upper portions 5, are clamped in position by a screw bolt or rotatable member 6 that extends freely through the member 2 into a threaded portion 7 on the member 1. Portions 8 of the members 1 and 2 are formed by means of cuts or slits 9 therein and are pressed laterally inward for cooperation with upper and lower portions 10 and 11, respectively, to constitute approximately vertical sockets for the reception of ends 12 and 13 of a hanger rod or suspension member 14 that is of substantially inverted U-shape and is suspended from a messenger cable 15. Initially, the ends 12 and 13 of the hanger rod 14, that is preferably of uniform circular cross-sec-

tional area throughout its length, and the portions 8, are substantially straight.

After the insertion of the ends 12 and 13, in the sockets formed by the portions 8, 10 and 11, pressure is applied transversely to the longitudinal axis of the hanger rod 14 to force the portions 8 toward positions in the planes of the portions 10 and 11. This action bends the ends 12 and 13 into substantially undulate-wave or corrugate form, with portions 16 bent slightly laterally between the portions 10 and 11 and, also, bends the portions 8 of the members 1 and 2 against the concave sides of the portions 16.

After the parts of the hanger are assembled in working position, a further tightening of the bolt 6 will not only tighten the hold of the clamping members 1 and 2 upon the trolley conductor 4, but will also tend to straighten out the interlocking curved portions of the suspension member 14 and the clamping members 1 and 2 and thereby increase the grip of the members 1 and 2 upon both the trolley conductor 4 and the ends 12 and 13 of the suspension member 14.

This structure withstands relatively great separating stresses and provides a very simple and economical device.

While I have shown and described a preferred form of my invention, I desire it to be understood that modifications may be made therein by those skilled in the art without departing from the spirit and scope of my invention as defined in the appended claims.

I claim as my invention:

1. A conductor hanger device comprising a hanger rod of substantially uniform cross-sectional area throughout its length and a trolley-conductor clamp having a rod-receiving portion, said rod and said rod-receiving portion being held together by pressing the same after assembly.

2. A conductor hanger device comprising a hanger rod, and a conductor clamping member having rod-receiving means consisting of a plurality of portions longitudinally displaced along, and alternately disposed on opposite sides of, the rod, said rod and said means being formed and related to interlocking engage each other.

3. A conductor hanger device comprising a hanger rod, and a conductor clamping member having rod-receiving means consisting of a plurality of portions longitudinally dis-

placed along, and alternately disposed on opposite sides of, the rod, said rod and said means being compressed laterally to interlock the same together.

5. A trolley-conductor hanger device comprising a pressed-metal conductor-clamping member having a portion pressed out of the plane of a wall thereof to therewith constitute rod-receiving means, and a hanger rod

10 having an end portion inserted in said receiving means, said end portion and said means being compressed laterally of the rod to form undulate-curve or corrugate interlocking portions in the rod and in the clamp-
15 ing member.

5. A trolley-conductor hanger device comprising a pair of pressed-metal conductor-clamping members each having a portion pressed out of the plane of a wall thereof to 20 therewith constitute a socket, and a hanger-rod member of substantially inverted U-shape having its free ends inserted in said sockets, said rod and said clamping members being compressed laterally opposite said 25 sockets to form undulate-curve or corrugate portions in the rod for interlocking the same with respect to the clamping members.

6. A trolley-conductor hanger device comprising a pair of pressed metal conductor-30 clamping members each having a substantially vertical wall portion and a portion pressed out of the plane of the wall to therewith constitute a vertical socket, and a hanger-rod member initially of substantially 35 inverted U-shape having straight free ends for insertion in said sockets, said rod and said clamping members being compressed laterally opposite said sockets to form longitudinal-wave or corrugate interlocking portions in the rod to position the clamping members.

7. A trolley-conductor hanger device comprising a pair of pressed-metal conductor-clamping members each having a portion of 45 arcuate form that is initially pressed out

wardly from a blank wall thereof to form a vertical socket and a hanger-rod member of substantially inverted U-shape initially having straight free ends for insertion in said sockets, said rod and said clamping members 50 being pressed together opposite said sockets to form compound bends in the said free ends and to interlock said arcuate portions against said bends.

8. A conductor clamp comprising an 55 elongated member having a portion of substantially wave shape and a conductor clamp having portions longitudinally spaced alternately on opposite sides of said member in interlocking relation thereto. 60

9. A conductor hanger device comprising a suspension member, a plurality of trolley-conductor clamping members through at least one of which said suspension member is threaded and means for securing said 65 clamping members one to another to more tightly grip said suspension member.

10. The combination with a trolley conductor and a suspension member, of connecting means comprising a pair of clamping members slotted to receive the ends of said suspension member and a movable member for tightening the grip of said clamping members upon said conductor and said suspension member upon the actuation of said 75 movable member.

11. The combination with a trolley conductor and a suspension member, of connecting means comprising a pair of clamping members through which the ends of said suspension member are respectively threaded and a bolt for securing said clamping members to said conductor and for increasing the grip upon said suspension member upon the tightening of said bolt. 80 85

In testimony whereof, I have hereunto subscribed my name this 29th day of January, 1921.

WILLIAM SCHAAKE.
